CLAIM

The ornamental design for a wash and cure machine, as shown and described.

DESCRIPTION

FIG. 1 is a front elevation view of a wash and cure machine showing my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view thereof.

The broken lines depict portions of the wash and cure machine that form no part of the claimed design.
